UNITED STATES PATENT OFFICE.

EMIL KELLER, OF VIENNA, AUSTRIA.

PROCESS FOR MANUFACTURING PAPER TUBINGS.

1,412,018.

Specification of Letters Patent. Patented Apr. 4, 1922.

Application filed May 22, 1919. Serial No. 299,056.

(GRANTED UNDER THE PROVISIONS OF THE ACT OF MARCH 3, 1921, 41 STAT. L., 1313.)

To all whom it may concern:

Be it known that I, EMIL KELLER, engineer, a citizen of the Republic Deutschösterreich, residing at Vienna, Deutschösterreich, have invented certain new and useful Improvements in Processes for Manufacturing Paper Tubings, (for which applications have been filed in Austria, filed Oct. 28, 1916; filed Aug. 25, 1917; filed Mar. 30, 1918; Hungary, filed May 10, 1917; filed Aug. 30, 1917; filed Jan. 23, 1919; filed Jan. 23, 1919; Germany, filed June 22, 1917; filed Sept. 1, 1917; Denmark, filed Dec. 16, 1918; filed Dec. 16, 1918; Switzerland, filed Dec. 9, 1918; Netherlands, filed Dec. 31, 1918; Norge, filed Jan. 6, 1919; Sweden, filed Dec. 20, 1918; Belgium, filed Jan. 31, 1919; Italy, filed Jan. 24, 1919; Finland, filed Jan. 24, 1919; in France and Turkey documents to be filed have been forwarded Jan. 2, 1919, and Sept. 7, 1918, respectively, but as yet no notice has been received of the applications having been filed,) of which the following is a specification.

In the art of manufacturing tubes, pipes or hose it has already been proposed to replace caoutchouc tubes by tubes or hose of paper having side walls provided with grooves or corrugations running transversely to the tube axis. The grooves or corrugations of this known type of tubes are however comparatively flat and distant from each other, so that a longitudinal section through the tube will offer the general aspect of a more or less steep sine curve. The flexibility and elasticity acquired by the tube by thus forming it will however be only very small. Besides grooves or corrugations of the form above described will not impart a sufficient force of resistance against strains directed transversely to the tube axis. A high degree of capacity of resistance against lateral strains and a high flexibility are however of primary importance for the practicability of a paper tube, which, unlike the caoutchouc tube, will not return to its original form, when depressed at some place or squashed or flattened at a sudden bend.

The object of this invention is an improvement in the art of manufacturing paper tubes which will result in a product which is a perfect substitute for the india rubber or caoutchouc tubings. The qualities required to attain this object are imparted

to the tube by corrugating a plain cylindrical tube in such a way that the walls of the grooves are closely abutting and are substantially perpendicular to the original plain surface of the tube or to the tube axis, so as to act as bracing pieces. Moreover a reserve of material is accumulated in said corrugations which may partly be paid out whenever the tube is subjected to bends or distortions, whereby the tube acquires an increased elasticity and flexibility as well as having the required strength against lateral forces that have the tendency to squash the tube or to depress or flatten it.

A preferred mode of carrying the invention into effect consists in compressing a paper tube provided with comparatively shallow grooves or corrugations at comparatively large distance from each other in axial direction, when moist, and subsequently drying the same. The preparatory grooving or corrugating of the paper tube preceding the afore mentioned final shaping may be produced by a nut co-acting with a threaded spindle, between which parts the paper tube to be corrugated is pushed or pulled through.

The process for manufacturing paper tubings according to this invention will be set forth with reference to the accompanying drawings, forming part of this specification, which however show only preferred forms of apparatus for carrying the invention into effect.

In the drawings:

Figure 1 illustrates a tube or hose manufactured by the present process, partly in side elevation and partly in longitudinal section;

Figures 2 and 3 illustrate portions of a tube flattened and spread out to show the paper layers.

Fig. 4 represents a cross section through the tube, and Figs. 5 and 6 represent diagrammatically arrangements for producing the preparatory grooving or corrugating preceding the final shaping of the side walls of the tube.

The improved tube or hose consists of paper layers 1, the number of which is suitably chosen according to the intended purpose. The layers are tightly wound upon each other on a cylindrical mandrel and the

adjoining layers are glued or connected together. The tube thus formed is then provided with grooves or corrugations in planes substantially perpendicular to its axis; 5 which are preferably wound to form a spiral or helix. As shown in Fig. 1 the grooves or corrugations closely abut, so that their crests and hollows are of semi-circular shape, the side parts of the grooves connecting said 10 crests and hollows being substantially perpendicular to the axis of the tube. The said side parts forming, as it were, a series of closely abutting rings constituting the side wall of the tube or hose, are united to form 15 a single continuous surface by means of the semi-circular crests and hollows, thus imparting to the tube a high resistive capacity against transverse forces working substantially perpendicular to the tube axis. Cor- 20 rugations or grooves having the form of a sine curve are apt to yield laterally on account of their inclined side parts, if any appreciable pressure is exerted upon them and are crushed or flattened more and more, 25 since only the insufficient resistance of a plain or only slightly corrugated paper wall will counteract the forces producing a deformation. Such yielding and flattening of the grooves or corrugations is, however, ren- 30 dered impossible, if they are arranged to closely abut in such a way that their side parts will be substantially perpendicular to the tube axis.

Moreover, by means of the closely abutting 35 grooves or corrugations an extraordinary increase of the flexibility and elasticity of the tube is produced. The side parts of the grooves 3, which are perpendicular to the tube axis, form, as it were, a sort of store or 40 reserve of material which suffices even in the case of very sudden turns or of ample lengthening or extension of the tube. Even in the case of very sudden bends the tube retains 45 its perfect circular cross section; no depressing or breaking on the inner and no flattening on the outer side will occur, as is the case with ordinary paper tubes having flat and not closely abutting corrugations, which frequently are completely squeezed together at 50 sudden bends of the tube.

A special advantage of the improved paper tube consists in the fact, that the close vicinity of the grooves or corrugations causes the formation of sharp bending edges, which 55 facilitate the return into the original shape after a deformation due to some violent influence.

A further increase of the flexibility and elasticity is obtained according to this invention by gluing or cementing the paper layers 60 1 only at certain places and by distributing these places uniformly along the circumference of the tube. As shown in Figs. 2 and 3, two superposed paper layers are prefer- 65 ably glued or cemented merely along axial

or helical strips or at certain places of such a line or curve, and the places glued of the superposed layers are staggered, in order to obtain a uniform distribution along the whole circumference (see Fig. 4). The inner and outer margins of each paper layer are of course likewise glued or cemented to the adjoining layer. 70

Gluing or cementing only at intervals allows of a very small displacement of the layers relatively to each other, which will occur, when a pull slightly flattening the grooves or corrugations 3 is caused by bending or stretching the tube. This lateral play of the paper layers, however small, adds greatly to 75 80 the flexibility and elasticity of the tube.

The arrangement for producing the shallow grooves or corrugations essentially consists of a spindle 5 threaded at 6 and of a nut 7, preferably made in two parts. The paper tube to be grooved is led through between spindle 5 and nut 7, the thread of both being arranged at a distance correspond to the thickness of the paper tube. 85

In the embodiment of the invention shown 90 in Fig. 5 the threaded spindle is rotatably journaled, the nut being capable of sliding along the spindle, while secured against rotation. The paper tube 8, after having first been slightly moistened, is then slipped over the spindle and secured at one end by some suitable locking device 9 to the spindle 5, so as to be able to rotate with said spindle. Then the nut 7 is slid over the end of the paper tube 8 and the spindle together with 100 the tube is rotated. The threads of the nut force the side walls of the tube into the threads of the screw spindle 6, whereby the desired grooves or corrugations are produced. Meanwhile the nut is shifted alongside the spindle (to the left in the drawing). After having passed over the whole tube the nut is put aside or removed and the locking device 9 is released. The grooved or corrugated tube is then secured against rotation, 110 for instance by simply taking hold of it by hand and the spindle 5 is again rotated. The paper tube then slides along the spindle and may be removed from it, after having left the threaded part 6 the spindle being for 115 this purpose lifted from its bearings.

To provide grooves or corrugations along the whole length of the paper tube, the following process may be adopted. After having slipped the plain or smooth paper tube 120 8 over the threaded spindle 5, the nut 7 is put upon its further end (at the right in Fig. 5) and is then held by hand and thus secured against rotation; the spindle is then rotated. Having thus provided a short portion of the 125 tube with grooves or corrugations the spindle is arrested and the grooved or corrugated portions (the right end of the tube in Fig. 5) is then secured to the spindle 5 by means of the locking device 9, which in this case 130

is preferably also threaded at its inner face. The spindle 5 is then again rotated until the nut has passed over the whole paper tube.

The grooves or corrugations thus produced in the side wall of the tube present in a longitudinal section, as shown in Fig. 6, the form of a more or less flat undulation or sine curve. Such grooves or corrugations impart a certain flexibility to the paper tube, 10 as already mentioned, which however, is by far too small to enable said tube to form an effective substitute for a caoutchouc tube. besides the capacity of such a tube to resist 15 efficiently against transversal strains seeking to depress or flatten the side walls is by far too small.

To increase the flexibility, elasticity and the capacity of resistance against lateral forces, the paper tube, slightly corrugated 20 in the way above set forth, is subjected to a compression in axial direction upon a rod, while still rather moist and is then dried in this condition. By this treatment the grooves or corrugations are firmly pressed 25 against each other and very much deepened (Fig. 1) whereby the intermediate side parts between the crests and hollows of the corrugations leaving their original inclined position are assuming a position perpendicular 30 to the tube axis.

Such grooves or corrugations impart to the paper tube such a high degree of flexibility, elasticity, and capacity of resistance against lateral forces that it forms in every 35 respect a perfect substitute for the india rubber or caoutchouc tube. Such a tube may be bent quite as sharply as a caoutchouc tube and even more so without being squashed or flattened, this being the result 40 of the fact, that the corrugations form as it were a store or reserve of material, which may partially be paid out, when the tube is bent. A store or reserve of material sufficient for the sharpest bends is however only 45 obtained, when the corrugations are of sufficient depth, i. e. of a depth not less than the distance between a crest and a hollow, when they are closely abutting, and are afterwards compressed to store up as much material as 50 possible within a given length.

This compression, moreover, by causing the side walls of the corrugations to run transversely to the tube axis, so that they are substantially perpendicular to the original 55 plain cylindrical surface of the uncorrugated tube, results in a capacity of resistance against any deformation of the cross section of the tube and against any squashing or depression of the same, which surpasses that 60 of the strongest caoutchouc tubes. This capacity of resistance is even still present at sharp bends, whenever, notwithstanding the fact that part of the reserve of material accumulated within the corrugations is paid 65 out to compensate for the increased length

of the arc at its outer side, there are some traces of said corrugations still left.

The capacity of resistance may be further increased without notably impairing the flexibility and elasticity of the tube by increasing the number of the paper layers forming the walls of the tube. 70

The axial compression of the corrugated paper tube may be effected simultaneously with the unscrewing of the paper tube from 75 the threaded part 6. (Figs. 5 and 6.) For this purpose the tube needs only some pressing in the direction of its escape, to cause the shallow grooves or corrugations immediately after they exit from the threaded part 80 6 to be effectually compressed along bending edges performed by the screw threads. Drying is again subsequently performed upon a rod in this compressed condition.

In the modified form of arrangement 85 shown in Fig. 6, the nut 7 and the spindle 5 remain stationary while on the contrary the tube 8 is rotated around the spindle, and thus is pulled through between the nut 7 and the threaded part 6 of the spindle, with 90 the result that the corrugations or grooves are formed upon its side walls. The corrugated tube then leaves the apparatus at its right hand end over the free end of the spindle. 95

The arrangement shown in Figs. 5 and 6 is adapted only for corrugating cylindrical tubes of limited length. If however, in the arrangement according to Fig. 6 the threaded spindle as well as the nut 7 are rotated 100 in the same direction, while the tube is secured against rotation, the said arrangement will be equally adapted for the treatment of endless paper tubes. The paper tube to be corrugated in this case is shifted 105 in an axial direction; it may be made on the apparatus itself by rolling or winding the paper layers upon an extension of the spindle 5. 110

It is preferable to use screw threads in 110 the nut and—with the arrangement shown in Fig. 6—also on the spindle, which are tapered between the discharge and the admission end, so that the threads will perform the desired shaping of the walls only by degrees and therefore very softly. Besides it will be of advantage, especially with the arrangement according to Fig. 6 to impart a rapid rocking motion around the geometric axis of the threaded spindle 5 to the nut 7, 120 the formation of the grooves or corrugations being thus facilitated and any roughening or scratching of the paper layers prevented. 125

The process described for producing the preparatory corrugating or grooving preceding the definite and final shaping allows very rapid working notwithstanding the very great simplicity of the apparatus used. The product thus obtained is a paper tube having absolutely uniform grooves or corrugations. 130

gations with a smoothly polished surface free from crumples or creases. A special advantage of the process consists in the fact that a heavy compression of the paper layers forming the walls of the tube will occur at its passage between the threads of the spindle 5 and the nut 7. As a result of this compression the superposed paper layers will conjointly and uniformly bear every strain. After the axial compression has taken place a tube or hose will be produced from the paper tube, which, owing to the closely abutting grooves or corrugations, is flexible and elastic like a caoutchouc tube and possesses a high capacity of resistance against depression or flattening.

What I claim is:

1. The art of manufacturing flexible paper tubings capable of retaining their cross section, when subjected to bends, or to lateral strain which consists in forming a paper tube having a plain cylindrical surface, in moistening the same, in shaping said surface into a continuous series of ascending and descending peripheral wall parts, closely abutting along their adjacent faces and in subsequently drying the same.

2. The art of manufacturing flexible paper tubings capable of retaining their cross section, when subjected to bends, or to lateral strain, which consists in forming a paper tube having a plain cylindrical surface by gluing together a series of superposed layers of paper in moistening the formed tube, in shaping its surface into a continuous series of ascending and descending wall parts closely abutting along their adjacent faces and in subsequently drying the same.

40 3. The art of manufacturing flexible paper tubings capable of retaining their cross section, when subjected to bends, or to lateral strain, which consists in forming a paper tube having a plain cylindrical surface, in moistening the same in shaping its surface into a continuous series of closely abutting peripheral wall parts, substantially perpendicular to the original plain surface of the tube and capable of effective resistance to lateral strain and in subsequently drying the same.

45 4. The art of manufacturing flexible paper tubings capable of retaining their cross section, when subjected to bends or to lateral strain, which consists in forming a paper tube, having a plain cylindrical surface, in moistening the same, in providing said surface with an uninterrupted series of corrugations having closely abutting intermediate side parts between their hollows and crests substantially perpendicular to the original plain surface of the tube, the intermediate side parts of said corrugations forming peripheral wall parts of the tube capable of effectively resisting to lateral

strain and in subsequently drying the tube when thus shaped.

5. The art of manufacturing flexible paper tubings capable of retaining their cross section, when subjected to bends or lateral strain, which consists in forming a paper tube, having a plain cylindrical surface, in moistening the same, in providing said surface with an uninterrupted series of corrugations running along a helix, the pitch of said helix being so chosen, that the intermediate side parts between the hollows and crests of said corrugations are closely abutting along their adjacent faces, and in subsequently drying the tube, when thus shaped.

6. The art of manufacturing flexible paper tubings capable of retaining their cross section, when subjected to bends, or lateral strains, which consists in forming a paper tube, having a plain cylindrical surface, in moistening the same, in providing said surface with an uninterrupted series of corrugations, running along a helix and having intermediate side parts between their hollows and crests substantially perpendicular to the original plain surface of the tube, the pitch of said helix being so chosen, that the said intermediate side parts are closely abutting along their adjacent faces and in subsequently drying the same.

7. In the art of manufacturing flexible paper tubings by corrugating a formed and moistening paper tube having a plain cylindrical surface, compressing the corrugated tube until the side parts of the corrugations are closely abutting and drying the tube, when compressed.

8. The art of manufacturing flexible paper tubings capable of retaining their cross section, when subjected to bends, or to lateral strains, which consists in forming a paper tube, having a plain cylindrical surface, in moistening the same, in providing said tube with a continuous series of corrugations having inclined intermediate parts between their hollows and crests, in compressing the corrugated side walls to make the said intermediate side parts closely abut along their adjacent faces and in subsequently drying the tube when thus shaped.

9. The art of manufacturing flexible paper tubings capable of retaining their cross section, when subjected to bends or to lateral strains, which consists in forming a paper tube, having a plain cylindrical surface, in moistening the same, in providing said tube with a continuous and uninterrupted series of corrugations having inclined intermediate parts between their hollows and crests in compressing the tube in axial direction until the said intermediate parts are closely abutting along their adjacent faces, and making them assume a position substantially perpendicular to the

- original plain tube surface, in which they are rendered capable to effectively resist lateral strains and in subsequently drying the tube, when thus shaped.
5. 10. The art of manufacturing flexible paper tubings capable of retaining their cross section, when subjected to bends or to lateral strain, which consists in forming a paper tube having a plain cylindrical surface, in moistening the same, in providing said surface with a continuous series of corrugations having inclined intermediate parts between their hollows and crests in compressing the corrugated side walls, the depth of the compressed corrugations being not less than the distance between a crest and a hollow in this state to form and to accumulate as high a reserve of material as possible within a given length, said reserve being paid out at bends 10 and in subsequently drying the tube when thus shaped.
11. The art of manufacturing flexible paper tubings, capable of retaining their cross section, when subjected to bends or to lateral strain, which consists in forming a paper tube having a plain cylindrical surface, in moistening the same, in providing it with a continuous series of corrugations having inclined intermediate parts between their hollows and crests in compressing the corrugated side walls until the same are assuming a position substantially perpendicular to the original plain surface to provide the tubing with a wall capable of effectively resisting 25 to lateral strains the depth of the corrugations when compressed being not less than the distance between a crest and an adjacent hollow, to form and to accumulate as high a reserve of material as possible within a given 30 length of the tubing to be paid out, when the tubing is subjected to bends and in subsequently drying the tube when thus shaped.
12. In the art of manufacturing paper tubings, corrugating a moistened paper tube, having a plain cylindrical surface by passing it between two threaded members each with a plurality of threads and by causing a relative rotatory movement to take place between one of said members and said tube, the 45 threads on said members being tapered in the axial direction, whereby a gradually increasing depth will be given the coils during 50 their formation on the tube.
13. In the art of manufacturing paper tubings, corrugating a moistened tube having a plain cylindrical surface by passing it between two threaded members and by causing a relative rotatory movement to take place between one of said members and the 55 paper tube, to force its side walls into the threads of said members and in compressing the side walls thus corrugated after their 60 having emerged between said members.
14. The art of manufacturing paper tubings capable of retaining their cross section 65
- when subjected to bends or to lateral strains, which consists in forming a paper tube, having a plain cylindrical surface, in moistening the same, in passing it between two threaded and engaging members, by causing a relative rotatory movement to take place between one of said members and the tube, to force the side walls of the tube into the threads of said members in compressing the corrugated side walls when emerging between said members and in subsequently drying the tube 70 when thus shaped.
15. The art of manufacturing paper tubings capable of retaining their cross section, when subjected to bends or to lateral strain 75 which consists in forming a paper tube having a plain cylindrical surface and peripheral walls formed by gluing together a series of superposed layers of paper in moistening the same, in passing it between two threaded 80 members, one of them being a spindle and the other a nut, the diameter of the threads differing to an extent corresponding substantially to the thickness of the superposed paper layers, in causing a relative rotatory 85 movement to take place between one of said members and the tube, to force the side walls of the tube into the threads of said members thus drawing the tube forward and at the same time heavily compressing the superposed layers forming its side walls, in compressing said tube in axial direction after 90 its having emerged between said threaded members and in subsequently drying the same, when thus shaped.
16. The art of manufacturing paper tubings capable of retaining their cross section, when subjected to bends or to lateral strain, which consists in forming a paper tube, having a plain cylindrical surface, in moistening 95 the same, in providing said tube surface with a continuous series of corrugations having inclined intermediate parts between their hollows and crests by causing it to pass between two threaded members, one being a 100 spindle passing through the hollow of the tube and the other a nut surrounding it, the thread of said members differing in their diameter to an extent substantially corresponding to the thickness of the side wall of the 105 tube in causing relative rotatory movement to take place between said tube and one of said members, thus forcing the side walls of the tube into the threads of said members, the pitch of said threads being chosen to allow 110 inclined intermediate parts between the hollows and crests of the corrugations caused by the threads, in then compressing the corrugated side walls by exerting an axial pressure on the tube to cause said intermediate 115 parts to closely abut and in subsequently drying said tube when thus shaped.
17. The art of manufacturing paper tubings consisting in moistening and corrugating the side walls of a plain cylindrical 120
- 125
- 130

paper tube, compressing its side walls after their having been corrugated and drying said tube while maintaining it in a compressed state.

- 5 18. The art of manufacturing paper tubings forming a plain paper tube by gluing together a series of paper layers, corrugating said tube, moistening the same, exerting an axial pressure on said tube when thus corrugated to cause the side parts of the corrugations to closely abut and drying the tube while maintaining said axial pressure.
- 10

- 15 19. The art of manufacturing paper tubings, capable of retaining their cross section when subjected to bends or to lateral strain,

which consists in forming a paper tube having a plain cylindrical surface, in corrugating the same by passing it between two threaded members and causing a rotatory movement to take place between one of said members and the tube, in compressing the tube thus corrugated by exerting a pressure in axial direction and by drying the tube while maintaining it in a compressed state.

In testimony whereof I have affixed my 25 signature in presence of two witnesses.
